OIL BURNER

Lynn Otis Selby, Cromwell, Conn., assignor to The
Sparmal Engineering Corporation, a corpora-
tion of Connecticut

Application March 4, 1939, Serial No. 259,880

9 Claims. (Cl. 158—28)

My invention relates to oil burners.

It has among its objects to provide an improved controlling mechanism for such burners, and particularly for such burners of the type including a preheating burner, herein called the distillate burner, and a main burner, herein called a power burner, preheated and maintained hot by the distillate burner ready for starting and operation at any time in accordance with heating demands of the system. A further object of my invention is to provide improved controlling mechanism whereby both burners may be controlled and co-ordinated in their operation in such manner that following lighting of one burner and operation of a manual control member, the two burners are successively brought into full operation. A still further object of my invention is to provide such improved controlling mechanism having improved means for controlling both burners whereby both burners are started and stopped in an improved manner and whereby the power burner is also controlled in an improved manner during operation of the distillate burner. These and other objects and advantages of my improved construction will, however, hereinafter more fully appear.

In the accompanying drawing I have shown for purposes of illustration certain embodiments which my invention may assume in practice.

In the drawing:

Fig. 1 is a side elevation partially in section of a combined distillate and power burner equipped for use with my improvement;

Fig. 2 is a wiring diagram of the electric control mechanism therefor;

Fig. 3 is an enlarged detail sectional view showing the seepage supply means on the solenoid valve of the distillate burner, and

Fig. 4 is a detail view of the time switch.

In this illustrative construction, I have shown a combined distillate and power burner of the construction described and claimed in my co-pending application Serial No. 156,989, filed August 2, 1937, the same having improved controlling mechanism whereby, following igniting of the distillate or preheating and maintaining burner, generally indicated at 1, and subsequent operation of a manual control member 2, the fuel supply in the main, or power burner, generally indicated at 3, is automatically started after a predetermined time interval, the two burners thereafter continuing in operation with the power burner automatically cut in and out of operation in accordance with the demands for heat, as needed, while the distillate burner maintains the

power burner at such temperature as to be ready to start at any time.

The vaporizing chamber 1a of the distillate burner is herein provided with an oil supply line 4 which supplies fuel to its carbon leg 5 from a constant level float chamber 6 as in my previously mentioned application. However, herein the maximum fuel supply to the burner base is controlled by a usual metering valve 7, and a pipe 8 herein is provided between the float chamber 6 and the pipe 4, and a solenoid valve 9 is provided to control the flow to the burner base. Further, it will be noted that although the distillate burner may be manually ignited as, for example, with a usual taper, I have shown the same as provided with an electric spark plug 10 adapted to ignite the outer wick 11 which, in turn, ignites the inner wick 12 through any usual means. Herein, also, the spark plug 10 and wick 11 are connected in circuit with a secondary coil 13 of a transformer T having its primary coil 14 connected across the line L and controlled by a suitable switch 15, herein in the form of a push button. Thus, with a flat portion 16 provided on the stem of the solenoid valve 9 (Fig. 3), it is possible, when this valve is closed, for a small quantity of oil to seep from the chamber 6 into the burner base in such manner as to maintain the wicks 11 and 12 saturated and thereby enable the same to be ignited at any time by operation of the spark plug 10, although it will, of course, be understood that this seepage will not be sufficient to maintain combustion in the burner when the valve 9 is closed. Consequently, when the push button 15 is operated, the wick 11 will be ignited, while the solenoid valve 9 will be subsequently opened by my improved controlling mechanism, as herein-after described.

Referring to the power burner, the same herein is also of the general construction described in my above mentioned application, including a vaporizing chamber 17 disposed axially within the vaporizing chamber 1a of the distillate burner and having an air supply tube 18 extending axially upward therethrough; this air mixing with the vapor rising from the chamber 17 and igniting therewith immediately adjacent the upper end of the air tube. Herein, as in my previous construction, air is supplied to the air tube 18 from a suitable blower 19 driven by an electric motor 20 and having its draft suitably adjustable as by a shutter 21; the air supply from the blower being delivered to the tube 18 through a supply pipe 22. Herein, however, the fuel supply to the vaporizing chamber 17, while indirectly connected

to the constant level fuel chamber 6 and controlled by a metering valve 23, herein has this metering valve establishing the maximum flow of fuel, and has a pipe 24 connected between the chamber 6, and a pipe 25 connected to the vaporizing chamber 17, as well as a solenoid valve 26 controlling the flow between the pipes 24 and 25. Here, it will also be noted that this solenoid valve 26 is adapted completely to shut off the supply of oil to the power burner, as distinguished from permitting seepage as referred to heretofore in connection with the valve 9 in the distillate burner. Thus, whenever the solenoid valve 26 is opened, oil will flow by gravity from the constant level chamber 6 into the power burner vaporizing chamber 17, and, when the distillate burner has brought the vaporizing chamber to a sufficiently high temperature, the power burner will start as a result of the ignition of the vapor in the chamber 17 as it emerges therefrom and is mixed with the air from the air supply pipe 18, immediately adjacent the top of the latter pipe.

Cooperating with the above distillate and power burner mechanisms is improved controlling mechanism for effecting operation of the same in the desired sequence automatically following lighting of the distillate burner and operation of the manual control member 2.

Referring first to the control of the distillate burner, it will be noted that, as shown in Figure 2, the solenoid valve 9 of the distillate burner has its coil 27 in a conductor 28 connected between a line conductor 29 and a stationary terminal 30 on a suitable switch base 31 on which the control member 2 is pivoted. Here, it will also be noted that a contact 32 is carried on the pivoted control lever 2, and that the latter electrically connects this contact with the other line conductor 33. Moreover, it will be observed that a ratchet 34 is provided around the pivot 35 of the lever 2 to require clockwise rotation thereof. Attention here is also directed to the fact that another contact 36 is carried on the switch base 31 and spaced from the contact 30 in such manner as to be engaged by the contact 32 in the last contact engaging position of the latter; this contact being connected to the conductor 28 by a conductor 37. Thus, it will be evident that with the wick 11 ignited, movement of the control lever 2 from the "off" position, indicated in full lines in Figure 2, and in a clockwise direction, will bring its contact 32 into engagement with the contact 30 as shown in dotted lines, and thereby actuate the coil 27 of the solenoid valve 9 controlling the oil supply to the distillate burner, in such manner as to open this valve and permit the distillate burner thereafter to operate normally. However, when the lever 2 is swung to disengage the contacts 32 and 30, it will also be noted that this solenoid valve 9 will again be opened by reason of the engagement of the contact 32 with the contact 36.

Referring to the control mechanism for the power burner, it will be observed that cooperating controlling mechanism is provided, whereby the power burner is controlled by the member 2 in an intermediate position of the latter. Herein, a contact 38 is provided on the base 31 adjacent the contact 30, both of these contacts being adapted to be bridged by the contact 32 when the lever 2 is in the "on" position indicated in dotted lines. This contact 38 is connected by a conductor 39 to any suitable time switch 40 adapted to close a circuit after a predetermined time interval. Obviously, this time

switch may be either mechanically controlled as by a dash-pot or clock mechanism, or electrically controlled as by a thermostat or synchronous electric motor, and it will be understood that I do not wish to be restricted as to the type of time switch provided. Herein, I have shown a well known type of thermostatic switch including a heating coil 40a of high resistance and suitably heat insulated from a bimetallic contact carrying element 40b heated thereby and adapted to flex and engage a contact 40c after the desired interval. Further, the current flow through the contact 40c of the time switch controls the current flow through conductor 41 to the fan motor 20 and further controls the current flow through a conductor 42 which is connected to a suitable pressurestat switch 43 in series with the coil 44 of the solenoid valve 26 of the power burner. Consequently, when the control lever 2 is moved into its "on" position to bridge the contacts 30, 38, the time switch will be energized and started at the same time that a full or operating supply of oil will be supplied through the solenoid valve 9 to the distillate burner. However, after the time switch 40 has been energized for a predetermined interval of sufficient length to permit the distillate burner to bring the vaporizing chamber of the power burner to the required temperature, preferably for a period of from fifteen to twenty minutes, the time switch 40 will then close its normally open contacts to enable current to flow from the conductor 39 through the conductors 41 and 42 to start the motor 20 of the blower 19 and to open the valve 26 of the power burner. Thereafter, both the distillate burner and the power burner being supplied with full supplies of oil, the same will operate together so long as the contact member 2 remains in its "on" position, and the pressure developed in the boiler 45 does not exceed a certain amount. Should, however, this pressure limit be reached, the pressurestat switch 43, which is responsive to boiler pressure, will be operated in a well known manner to break the circuit to the coil 44 of the power burner valve 26 and thereby permit the latter to close and shut down the power burner, which will remain shut down until the pressure drops and the pressurestat switch 43 returns to its normal or circuit closing position.

In the operation of my improved burner, the push button 15 is preferably operated as the first step in starting, and the control lever 2 is then moved from "off" to "on" position, although obviously the igniting mechanism will function should the push button be operated after the member 2 has been moved into "on" position. Thus, the user has only to push the push button and move the control lever 2 into "on" position; subsequent starting of the power burner after a proper time interval being accomplished automatically through my improved mechanism. Here, it will also be understood that the time switch, which is normally open, will close the circuit of the power burner valve and the fan motor when the vaporizing chamber of the power burner, disposed axially within the vaporizing chamber of the distillate burner, has been sufficiently heated by the distillate burner to bring the axial portion of the base, including the parts comprising the power burner vaporizing chamber, to such a temperature that sufficient vapor will be generated in the power burner vaporizing chamber to ignite at the top of the air tube when mixed with the air flow, and support combustion.

Further, the control of the mechanism by the pressurestat switch 43 is automatic, the power burner being started and stopped in accordance with pressure conditions and without any starting delay so long as the member 2 remains in "on" position. Also, it will be observed that when less steam is required than that resulting from the operation of the power burner, it is possible to move the contact 32 out of "on" position and into engagement with the contact 36, whereupon the power burner will be manually cut out while the distillate burner is maintained in operation. Here it will also be noted that the ratchet mechanism requires movement of the member 2 relative to contacts 30, 38 and 36 in a predetermined sequence, in such manner as, through insuring a predetermined rotation of the member 2, to minimize confusion in operation.

As a result of my improved construction, it is made possible to eliminate altogether the long period of manual supervision heretofore incident to the starting of the combined distillate and power burner of my above mentioned application. Instead, all that an operator has to do is to light the distillate burner by pushing the push button and then throw the control member into "on" position, whereupon the distillate burner operates normally and, after the parts of the power burner have been brought to the desired temperature by the distillate burner, the power burner starts automatically. Further, it requires no further supervision by the operator when maximum pressure is required throughout the operating day, the operator only having to shut down the burner at the end of the day. Also, during the day the pressurestat switch will turn the power burner off and on, as necessary, to maintain the desired pressure; it here being noted that circuit through the time switch is maintained while the pressurestat switch is open, and further that the fan motor is kept running so that when the pressure drops, the power burner will be started again without delay. Moreover, if the operator knows that there will be a considerable period during the day when the demand for steam will be less than normal, as, for example, when only one, as distinguished from a considerable number of machines, are operating from the pressure source, it is possible to cut out the power burner during this interval and run only on the distillate burner.

It will be understood that while I have herein referred to a vaporizing chamber 1a and a carbon leg 5, whether vaporization occurs in one or the other depends upon the temperature at which the burner is operating, vaporization occurring in chamber 1a when the burner is relatively cold, as when starting, and in the carbon leg when at operating temperature, as is well-known in the operation of burners of this type.

While I have in this application specifically described one embodiment which my invention may assume in practice, it will be understood that this form of the same is chosen for purposes of illustration, and that the invention may be modified and embodied in other forms without departing from its spirit or the scope of the appended claims.

What I claim as new and desire to secure by Letters Patent is:

1. In combination, a pair of oil burners each having a gravity oil supply and one burner preheating and maintaining the other at operating

temperature, electromagnetically operated valves controlling said oil supplies, mechanism for starting said preheating and maintaining burner having means for opening the valve of said burner to effect a gravity flow from its oil supply, and mechanism for starting said other burner having time controlled means for automatically opening the valve of said other burner to effect a gravity flow from its oil supply only when said preheating burner has operated for a sufficient time to bring said other burner to operating temperature and while maintaining said preheating and maintaining burner in operation throughout the operation of said other burner.

2. In combination, a pair of oil burners each having a gravity oil supply and one burner requiring preheating at high temperature for a substantial period and the other adapted so to preheat said first mentioned burner, electromagnetically operated valves controlling said oil supplies, and mechanism for starting said burners having means for opening the valve of said preheating burner to effect a gravity flow from its oil supply, time controlled means operative while said valve remains open for automatically opening the valve of the preheated burner to effect a gravity flow from its oil supply only when said preheating burner has operated for a sufficient time to bring said preheated burner to operating temperature, and means for intermittently opening and closing the valve to said preheated burner while operating the preheating burner to maintain the preheated burner at starting temperature.

3. In combination, a pair of oil burners each having a gravity oil supply, a combustion chamber and a vaporizer, and one burner preheating the vaporizer of the preheated burner to effect transfer of the oil from the vaporizer thereof, by expansion of its heated vapors, to the combustion chamber thereof, electromagnetically operated valves controlling said oil supplies, mechanism for opening the valve for said preheating burner to effect a gravity flow from its oil supply, time controlled mechanism controlled by said first mentioned mechanism for automatically opening said preheated burner valve when the other burner has been brought to operating temperature by said preheating burner to effect a gravity flow from its oil supply, and means for intermittently starting and stopping said preheated burner in response to demands for heat while maintaining the preheating burner operating sufficiently to maintain the vaporizer of said preheated burner sufficiently hot to vaporize fuel therein and permit immediate starting of said preheated burner at any time.

4. In combination, a pair of oil burners each having a gravity oil supply, a combustion chamber and a vaporizer, and one burner preheating the vaporizer of the preheated burner to effect transfer of the oil from the vaporizer thereof, by expansion of its heated vapors, to the combustion chamber thereof, electrically operated plunger valves controlling said oil supplies, and electric controlling mechanism for said valves including a switch for opening the valve for said preheating burner to effect a gravity flow from its oil supply, time controlled means controlled by said switch for automatically opening the valve of said preheated burner when the latter burner has been brought to operating temperature by said preheating burner to effect a gravity flow from its oil supply, and means for intermittently starting and stopping said preheated

burner in response to demands for heat while maintaining said preheating burner operating sufficiently to maintain the vaporizer of said preheated burner sufficiently hot to vaporize fuel therein and permit immediate starting of said preheated burner at any time.

5. In combination, a pair of oil burners each having a gravity oil supply, a combination chamber and a vaporizer, and one burner preheating the vaporizer of the other, electromagnetically operated valves controlling said oil supplies including a valve for said preheating burner having a constantly open seepage connection to the latter, a common manually operable control member for both burners, means controlled by the operation of said manually operable controlling member for initially opening the valve for said preheating burner to effect a gravity flow from its oil supply, means likewise controlled by the aforesaid operation of said manually operable controlling member for subsequently opening the valve for said preheated burner after a predetermined preheating operation of the latter by said preheating burner to effect a gravity flow from its oil supply, and means for opening and closing the valve controlling the oil supply to said preheated burner in response to varying demands for heat while maintaining the valve controlling the supply to said preheating burner constantly open and said preheated burner ready for immediate operation.

6. In combination, a pair of oil burners each having a gravity oil supply and one burner pre-heating the other, said preheated burner having a vaporizing chamber and an air supply coaxial with its vaporizing chamber and said vaporizing chamber surrounded and heated by said pre-heating burner, solenoid operated plunger valves controlling said oil supplies, mechanism for opening the valve of said preheating burner to effect a gravity feed from its oil supply, mechanism for starting said preheated burner having time control means for automatically opening the oil valve thereof to effect a gravity feed from its oil supply and supplying air to said air supply only when said preheating burner has operated for a sufficient time to generate sufficient vapor in the vaporizing chamber of said preheated burner to maintain combustion in the latter when said vapor is mixed with air from said air supply, and means for starting and stopping the preheated burner while continuing to supply air to the same and while maintaining the same heated by said preheating burner ready for starting at any time.

7. In combination, a pair of oil burners each having a gravity oil supply and one burner pre-heating the other, said burners having coaxial vaporizing chambers and said preheated burner having an air supply coaxial with its vaporizing chamber and disposed within the vaporizing chamber of said preheating burner, electromagnetically operated valves controlling said oil supplies, mechanism for opening the valve of said

preheating burner to effect a gravity flow from its oil supply, mechanism for starting said preheated burner having time control means for automatically opening the valve thereof to effect a gravity flow from its oil supply and supplying air to said air supply only when said preheating burner has operated for a sufficient time to generate sufficient vapor in the vaporizing chamber of said preheated burner to maintain combustion in the latter burner when said vapor is mixed with air from said air supply, and means responsive to the heat generated by said burners for automatically both closing the valve of said preheated burner and opening said valve independently of said time control means while maintaining the preheated burner preheated by said preheating burner and ready for operation.

8. In combination, a pair of oil burners each having a vaporizer and oil supply means, and one burner preheating the vaporizer of the other, electromagnetically operated valves controlling said oil supplies, electrically operated pressure air supply means for the preheated burner, a time delay switch controlling the circuits of said air supply means and the valve for said preheated burner, and a manually operative switch having a movable contact member and a cooperating contact engageable thereby in one position of said movable member and energizing the valve for the preheating burner and the time switch, whereby after a predetermined operation of the preheating burner oil and air will be supplied to the preheated burner, and another cooperating contact engageable by said movable member in another position thereof wherein the time switch is deenergized and only the valve for the preheating burner remains energized.

18. The preheating burner remains energized.
9. In combination, a pair of oil burners each
40 having a vaporizer and oil supply means, and
one burner preheating the vaporizer of the
other, electromagnetically operated valves con-
trolling said oil supplies, electrically operated
pressure air supply means for the preheated
burner, a time delay switch controlling the cir-
cuits of said air supply means and the valve for
45 said preheated burner, a manually operative
switch having a contact member and a cooper-
ating contact engageable thereby in one posi-
tion of said movable member and energizing the
valve for the preheating burner and the time
50 switch, whereby after a predetermined opera-
tion of the preheating burner oil and air will be
supplied to the preheated burner, and another
cooperating contact engageable by said movable
member in another position thereof wherein the
55 time switch is deenergized and only the valve
for the preheating burner remains energized,
and means operative only in said first mentioned
position of said switch in response to varying
demands for heat for interrupting the circuit
60 to the valve for the preheated burner, while the
valve for the preheating burner and the time
switch remain energized.
